UNITED STATES PATENT OFFICE

JAMES H. RAND, JR., OF TONAWANDA, AND LOUIS C. BROECKER, OF BUFFALO, NEW YORK, ASSIGNORS, BY MESNE ASSIGNMENTS, TO REMINGTON RAND INC., OF NEW YORK, N. Y., A CORPORATION OF DELAWARE

RECORD CABINET

Application filed February 2, 1924. Serial No. 690,282.

This invention relates to record or card index cabinets.

Heretofore record or index cabinets including a vertical series of substantially horizontal trays or supports on which the records or indices are displayed have been provided, the cabinets having rear and side walls and an open front, whereby the trays or supports may be withdrawn or partially withdrawn through the open front of the cabinet and the contents of the trays or drawers made available to the operator. With such constructions it has been impractical for more than one person to handle or operate the record or index trays in a tier of these devices, and the result has been that operators desiring to examine the records or work on the devices in the trays or supports are compelled to lose considerable time.

It has further been proposed to open the cabinets at opposite ends so that the trays may be withdrawn straight out from opposite ends of the cabinet. However, in such constructions the cards or record devices, being arranged transversely of the trays, are presented to the operator in proper position when the trays are withdrawn from one end of the cabinet, but are not in proper position to be worked upon when withdrawn from the opposite end of the cabinet, that is to say, the cards or record devices are rear end foremost and the labels, etc., cannot be readily read.

The objects of the present invention are to provide a cabinet or record enclosing device in which the records or index matter in different trays or supporting devices may be readily viewed or handled by different operators at the same time; also to provide a record or index cabinet from which the trays or supports may be withdrawn in more than one general direction preferably from two opposite sides, in such movements the cards or record devices being in proper position to be expeditiously viewed or worked upon; also to provide a record or index cabinet in which the trays or supports for the record or index matter are provided with improved means for supporting them when they are partially withdrawn from the cabinet. Further ob-

jects are to provide improvements in record or index cabinets in the other respects hereinafter set forth and claimed.

In the accompanying drawings:

Fig. 1 is a perspective view of a cabinet provided with a plurality of record displaying trays, said cabinet and trays being constructed and arranged in accordance with the preferred embodiment of the invention. 55

Fig. 2 is a sectional plan view of the cabinet, 60 showing one of the trays in closed position therein.

Fig. 3 is a fragmentary side view of the cabinet, partly in section.

Fig. 4 is a view, similar to Fig. 2, showing 65 the manipulation of the trays to expose the contents thereof at opposite sides of the cabinet.

Fig. 5 is a fragmentary horizontal section showing the locking position of the pivot pins 70 for the trays.

Fig. 6 is a fragmentary sectional plan of the cabinet showing the extreme outward operative position of a tray.

Fig. 7 is a fragmentary sectional plan 75 view of the locking means whereby the trays may be prevented from being withdrawn from the cabinet.

Fig. 8 is a fragmentary transverse section on an enlarged scale on line 8—8, Fig. 19. 80

Fig. 9 is a fragmentary sectional elevation on line 9—9, Fig. 6.

Fig. 10 is a fragmentary sectional elevation showing the lifted position of one of the tray retaining latches. 85

Fig. 11 is a fragmentary sectional elevation of the cabinet with two of the trays in inoperative position therein, on line 11—11, Fig. 3, on an enlarged scale.

Fig. 12 is a side elevation showing in 90 full and broken lines respectively the positions of the tray supporting legs of two trays, when withdrawn to operative positions.

Figs. 13 and 14 are fragmentary sectional elevations showing respectively the unlocked 95 and locked positions of the tray locking means.

Fig. 15 is a perspective view of one of the journal shoes for the adjustable tray supporting legs. 100

Fig. 16 is a fragmentary horizontal section of one of the adjusting devices for changing the adjustment of the tray supporting legs.

Figs. 17 and 18 are fragmentary elevations thereof, showing two different adjustments of the parts.

Fig. 19 is a plan view of one of the sliding connections for permitting the extension of the leg members.

Fig. 20 is a transverse section on line 20—20, Fig. 18.

The cabinet of this invention, generally speaking, is so constructed that the trays or supporting devices may be operated and the record or index matter on such trays or supporting devices viewed or worked upon from several positions relatively to the cabinet, thereby permitting work upon the index or record devices simultaneously by a number of operators disposed in different positions with respect to the cabinet, and at the same time presenting the index or record matter to the operator right side up and in the most favorable position to be worked upon.

In the embodiment of the invention shown, the cabinet proper is open at two opposite sides and the trays or supports are so mounted that they can be readily withdrawn from either one of these opposite sides of the cabinet. Thus, one operator may take a position at one side of the cabinet and another operator at the opposite side of the cabinet, and both will have free access to the records and may work without interruption simultaneously upon the records in the different trays or supports of the cabinet. While what is now considered the preferred form of this invention is illustrated, it is obvious that other sides of the cabinet may be opened or the operators disposed in different positions with respect to the cabinet without departing from the principle or spirit of this invention.

Referring to the drawings, A designates a cabinet which may be of any suitable construction, the cabinet shown having end walls B and C, a top D, and being provided with suitable partitions E on which the trays or record matter supports are adapted to be moved. In the preferred form shown, this cabinet is open at the opposite sides F and G.

The cabinet is provided with a plurality of record-matter supporting members or trays which are mounted in the cabinet so that they may be withdrawn or partially withdrawn from either of the open sides F or G of the cabinet and in such manner that the record or index matter on the supports or trays will be properly presented to the operator in the withdrawn positions of these supporting members. The supporting members or trays may be of any suitable form. In the embodiment of the invention shown, there are provided a plurality of trays 10 which have record supporting bodies or portions 11, side

flanges 12, preferably forming channels at the sides of the trays, fronts 13, and hinged or pivoted tail pieces 14. According to the invention, means are provided for mounting these supports or trays in the cabinet so that when withdrawn from either of the opposite sides F or G of the cabinet, the supporting devices or trays will be presented to the operator with the front ends extending out of the cabinet. The record or index matter, as usual, is arranged transversely in the supports or trays between the sides 12 so as to be readily legible or workable from side to side thereof when the operator is positioned at the front ends of the trays, this results in the index or record matter being presented to the operator in positions most favorable for his work, upon withdrawal of the trays. With such object in view, in the embodiment shown, the supporting members or trays are disposed in the cabinet with their opposite side edges or flanges 12 adjacent to and substantially parallel with the opposite open sides F and G respectively of the cabinet so that they may be swung in horizontal planes out of the cabinet, the pivots being adjacent the rear ends of the supporting members or trays. In this manner each tray 10 may be withdrawn from the cabinet with its front 13 extending outwardly from either side F or G, so that the records thereon may be viewed and read from side to side from the front of the tray. In the particular form shown, the tail pieces 14 (Fig. 2) are provided with bearing parts formed by openings or apertures as at 16 in the tail pieces of the trays. There is preferably provided a pair of these bearing parts for each tray disposed adjacent opposite sides of the tray, and pivot means are provided whereby, when the tray or support is swung outwardly from one side of the cabinet it will pivot on one of these bearing parts, and when swung outwardly from the other side of the cabinet it will pivot on the opposite bearing part. For this purpose, in the form shown, there is provided a pair of pivot pins or members designated respectively 17 and 18 (Figs. 2, 3 and 4). The openings in the tail pieces of the supports or trays are preferably circular in form and the pivot pins 17 and 18 are arranged so that when the trays are in an inoperative position in the cabinet, they will both extend through the apertures 16 with their axes coincident with the axes of said apertures, see Fig. 2. The cross sectional shape of the pivot pins is elongate as shown, the longest dimension being normally arranged substantially parallel with the open sides of the cabinet. The two longer faces of each pin are curved concentrically on arcs, the center of which is on the axis of the other pin, while the shorter sides are curved to form arcs of a circle coinciding with the apertures 16. The apertures 16 of the tail pieces connect with slots 16^a which extend to

the rear or free edges of the tail pieces, said slots being each curved on an arc the center of which also is the axis of the apertures 16 at the opposite side of the tray, and are so positioned that when the trays are in the cabinet, they will be in alinement or register with the pivot pins. The slots 16^a are of substantially the same width as the adjacent edge of the pivot pins. Thus, as shown in Fig. 4, when the trays are swung outwardly from one side of the cabinet they will pivot on the pivot pin adjacent the side to which they are swung by means of the aperture 16 in the tail piece at that side of the cabinet, and the pivot pin at the opposite side of the cabinet will pass out from the tail piece as the tray is swung, through the elongated slot 16^a or continuation of the opening 16 in the tail piece at that opposite side. It is obvious that a reverse operation ensues when the trays are swung outwardly from the other side of the cabinet.

In working on index or record devices of this general type, the operator usually withdraws the desired tray or support from the cabinet, leaving the tail piece 14 connected to the cabinet and allows the body portion 10 of the tray, which is then outside of the cabinet, to drop down to an inclined position and holds such tray or support in such inclined position while working upon the contents of the support or tray. The present invention includes means for limiting the extent to which the trays or supports may swing downwardly relatively to the tail pieces or to the cabinet, thereby insuring that the trays or supports, when withdrawn, are at all times in proper and uniform positions to be worked upon. The invention also includes means operating automatically upon withdrawal of the supports or trays for stopping such trays or supports in their proper operating positions and maintaining them in such positions until returned into the cabinet. These means are preferably actuated by the tray as it is swung downwardly when in its withdrawn position. In the form shown, the trays are provided with pairs of legs 22 (Fig. 1) which are actuated by the tray as it swings down so as to be automatically extended to support the tray in proper operating position. The free ends 23 of the legs are adapted to engage any suitable support, a portion of the cabinet in the form shown. The other ends of the legs are rigidly connected to pins 24 journalled at the sides of the trays. The pins 24 (Fig. 7) are preferably provided with crank portions 25 preferably positioned in the side channels 12 of the trays, and these crank portions are preferably connected to tail pieces 14 by means of links 26 (Fig. 12) which preferably extend in the side channel flanges 12 of the trays where they are out of view. The links 26 may be connected to the tail pieces by any

suitable means, as for example, the pins 27 shown in the form illustrated in Fig. 16, which extend transversely of the tail pieces. When the trays are withdrawn from the cabinet and the body of the tray lowered relatively to the tail pieces, the links 26 will restrain the outer ends of the cranks 25 and rock the pins 24 with the result that the legs will be swung downwardly out of alinement with the trays or supports to proper supporting position.

Means are also provided for adjusting these automatic tray-supporting means. With this purpose in mind, the supporting legs 22 for the trays are preferably extensible so that they may be adjusted to extend a greater or lesser distance from the tray. This may be done in any usual manner by constructing the legs in several sections and connecting them by means of a lock bolt or screw 28 (Fig. 1).

In order to adjust the "throw" of the legs 22, or the angle at which they project from the trays or supports, means may be provided whereby the angular position of the crank 25 for actuating the legs may be changed or varied. This may be done, as illustrated in Figs. 16-18, by changing the relative positions of the pins 24 which are shown as journalled in shoes or members 29 (Fig. 16) which are preferably positioned in the side channels of the trays or supports. The trays or supports are preferably provided with elongated apertures or slots 30 (Figs. 16 and 18) through which the leg actuating pins extend and the shoes 29 are held in one position or another in the channels of the trays by means of bolts 31 (Figs. 16 to 18) which are secured to the shoes and extend through slots 32 provided in the sides of the trays. The members 29 may be moved more or less toward or from the fronts of the trays in the channels and as the pivot pins 24 move with these members, the angle of the crank relatively to the body of the tray is changed and consequently the "throw" of the legs will be varied when actuated by the links 26, which are of fixed length.

The invention further includes means for releasably holding the tail pieces 14 of the trays or supports connected to the cabinet when the trays have been swung upon their pivots so that the body portions of the trays with the record matter thereon extend outside of the cabinet. For this purpose, the cabinets are preferably provided at opposite sides with parts which are adapted to engage and hold parts of the tail pieces of the respective trays when the trays are swung to cause them to project from the cabinet. In the form shown, the partitions E of the cabinet are provided with ribs or flanges 33 (Fig. 6) at the open sides of the cabinet and the tail pieces of the trays or supports are each provided with a transverse groove or de-

pression 34 preferably formed by a pair of spaced, parallel ribs or elongate bosses 34^a. Thus, as shown in Figs. 6 and 9, when a tray is swung out of the cabinet, pivoting on one of the pivot pins 17 or 18, the rib or flange 33 on the partition E beneath the tray engages in the transverse recess 34 in the tail piece 14 of the tray, and at the same time the side edge of the tail piece contacts with the side wall B of the cabinet. This ensures that the tail pieces will be held in proper positions. The trays and tail pieces may be wholly withdrawn from the cabinet by rotating the retaining pivot pin through ninety degrees by a mechanism to be described, and pulling the trays forward after they are in the projecting positions described. In such forward movement, the small ribs 34^a which form the transverse depression 34 may be sprung over the partition flanges 33 by a slight pull, permitting the tail pieces to escape from the cabinet. When it is not desired to wholly withdraw the tail pieces, the weight of the tray ensures that the tail pieces remain in position with their grooves 34 engaging the partition flanges 33.

In order to lock the trays in the cabinet, suitable means may be provided for preventing the pivot pins 17 and 18 from sliding out of the openings or slots 16^a in the tail pieces 14 of the trays. This being done, until released, there can be no pivotal movement of the tray. In the form shown, this is accomplished by providing means for moving the pivot pins 17 and 18 to and from positions where their reduced portions may enter the elongated slots 16^a in the tail pieces. In this construction the pivot pins are preferably provided with actuating levers or throw arms 35 (Figs. 13 and 14) whereby they may be turned, and as shown in Fig. 5, when the pivot pins are turned through an angle of 90° more or less, the long dimensions of the pivot pins are opposed to the elongated slots in the tail pieces and cannot pass through. The throw arms 35 may be housed in any suitable place, as for example, the recesses 36 (Fig. 13) in the top of the cabinet in which they are arranged so that their free ends extend to an accessible position outside the cabinet, from which place they may be readily actuated. Suitable means are also provided for locking these parts in closed positions. In the form shown for this purpose, there is provided a lock 37 (Figs. 3 and 14) which may be of usual type having a spindle 38 which is provided with a pair of cams 39. In locked position the cams project in the path of movement of an arm 40 on the lever 35 and when the arm is positioned between the cams it is there held against movement. In this position the long dimensions of the pivot pins block the slots in the tail pieces. To release the trays, to permit them to be swung out of the cabinet, the lock 37

is actuated to turn the spindle 38, the lever 35 may then be thrown to open position thereby turning the pivot pins 17, 18 so that their short dimensions register with the slots 16^a in the tail pieces 14, whereupon the trays 70 may be pulled out.

Means of suitable sort are also preferably provided for releasably maintaining the trays in alined position in the cabinet so that when not in use they will occupy such 75 position that they will be prevented from accidentally swinging outwardly and will always be in position to be grasped by an operator when it is desired to use them. The trays are preferably provided, at opposite 80 sides, adjacent their front ends, with handles or pulls 40^a, and the means for releasably maintaining the trays as stated are conveniently located so as to be actuated by the operator when grasping one of the pulls 40^a to 85 withdraw a tray. As shown in Figs. 10 and 11, the trays are provided at opposite sides with resilient spring fingers or members 41, the inner ends of which are secured to the body portions 10, and the outer free ends of 90 which extend through apertures 42 in the side walls 12 of the trays to positions beneath the pulls or handles 40^a. These fingers normally extend as shown in Fig. 11, and each finger has a depending, curved lug 44. 95

When a tray is in its inoperative position in the cabinet, the lugs 44 at opposite sides thereof will engage the opposite flanges 33 of the partition on which the tray rests, and prevent accidental movements of the tray out of either side of the cabinet. When, however, it is desired to withdraw a tray, the operator grasps a pull 40^a and presses upwardly against the free end of the adjacent finger piece 41, thereby diengaging its lug 44 from the flange 33. The tray may now be withdrawn. It is obvious that this action may take place at either side of a tray, the opposite finger moving inwardly away from its companion flange 33. Any other suitable device 100 may be provided for the purpose stated. 105

While the foregoing description relates to a cabinet having opposite open sides and having trays therein movable to operative positions out of either of these open sides, the invention is not necessarily limited to such construction, as the invention in its broadest sense discloses the combination of a cabinet, a horizontal tray arranged therein with its sides parallel to an open side of the cabinet, 110 and means for pivotally connecting said side so as to swing horizontally to an outward position and be then inclined downwardly so that the record thereon may be viewed or worked upon. Therefore, if desired, the cabinet could be constructed having only one open side, and with the slides arranged and movable in and out of this one open side, as stated, without departing from the spirit of this invention. 115

We claim as our invention:

1. A record cabinet having a plurality of open sides, a plurality of record-supporting members in said cabinet and having front and rear portions, said members being movable in and out of said cabinet, and a plurality of pivot members releasably connecting each of said supporting members to the cabinet, whereby said record-supporting members may be swung on one of said pivots to project out of one of the open sides of said cabinet or swung on another of said pivots to project out of another open side of said cabinet.

2. A record cabinet having a plurality of open sides, a plurality of record-supporting members in substantially horizontal positions in said cabinet and having front and rear portions, means pivotally and releasably connecting said record-supporting members at one end to said cabinet, whereby said record-supporting members may be pivotally swung out of any one of the open sides of said cabinet.

3. A record cabinet having opposite open sides, a plurality of record-supporting members formed to receive records in overlapping position having front and rear portions and movable into and out of said cabinet, said record-supporting members having side portions which close the otherwise open sides of the cabinets when they are in position therein, means pivotally connecting the rear portions of said record-supporting members to the cabinet having a plurality of selective pivots in said cabinet, whereby the record-supporting members may be selectively turned on one of said pivots and partially withdrawn from the cabinet with their front portions foremost, at either one of the opposite open sides of the cabinet.

4. A record cabinet having opposite open sides, a plurality of metal record-supporting members formed to receive records in overlapping position having front and rear portions and movable into and out of said cabinet, said record-supporting members having side portions which close the otherwise open sides of the cabinets when they are in position therein, means pivotally connecting the rear portions of said record-supporting members to the cabinet, whereby the record-supporting members may be turned on said pivots and partially withdrawn from the cabinet with their front portions foremost at either one of the opposite open sides of the cabinet, and said pivotal means being movable to and from positions to prevent said pivotal movement of said supports and maintain said record supports in closed positions in said cabinet.

5. A record cabinet having a plurality of open sides, a plurality of trays movable into and out of said cabinet, a plurality of pivot posts in said cabinet, and parts on said trays for engaging said posts, said posts and parts

being formed to pivot said trays on one of said posts when the trays are swung to project from the cabinet in one direction and to pivot on another of said posts when the trays are swung to project from the cabinet in another direction.

70

6. A record cabinet having a plurality of open sides, a plurality of trays movable into and out of said cabinet, a plurality of pivot posts in said cabinet, parts on said trays for engaging said posts, said posts and parts being formed to pivot said trays on one of said posts when the trays are swung to project from the cabinet in one direction and to pivot on another of said posts when the trays are swung to project from the cabinet in another direction, and means for turning said pivot posts to prevent swinging of said trays out of said cabinet in any direction.

75

7. A record cabinet having a plurality of open sides, a plurality of trays movable into and out of said cabinet, a plurality of pivot posts in said cabinet, parts on said trays for engaging said posts, said parts having slots extending to the outside of said trays, whereby when a tray is swung in one direction to project from the cabinet, the opposite post is permitted to escape from one of said tray parts so that the tray may have a pivotal movement on another of said posts.

95

8. A record cabinet having a plurality of open sides, a plurality of record trays formed to receive records in overlapping position movable into and out of horizontally disposed positions in said cabinet, said trays having hinged tail pieces whereby the trays may be suspended by said tail pieces in inclined projecting positions at either of the open sides of said cabinet, and a plurality of pivotal connections between said tail pieces and said cabinet whereby said trays may be selectively swung on one of said pivotal connections in horizontal planes to project at any one of the open sides of said cabinet.

100

9. A record cabinet having a plurality of open sides, a plurality of record trays movable into and out of horizontally disposed positions in said cabinet, said trays having tail pieces whereby the trays may be suspended by said tail pieces in inclined projecting positions at the open sides of said cabinet, a plurality of means in said cabinet pivotally engaging said tail pieces to permit said trays to be swung in horizontal planes to project from one or another of said open sides, and parts on said tail pieces engaging said pivotal means, certain of said parts being formed to disengage from said pivotal means when the trays are swung in one direction and others of said parts being formed to disengage from said pivotal means when the trays are swung in another direction.

115

10. A record cabinet having a plurality of open sides, a plurality of record trays movable into and out of said cabinet, a pair of

120

125

130

5 pivot posts in said cabinet, said trays having end portions provided with bearing portions for engaging said pivot posts and with open slots extending from said bearing portions to the edges of said end portions, said pivot posts having parts rounded on arcs having their respective axes in the axes of the opposite pivot posts, whereby when the trays are swung in one direction they will pivot 10 on one of said pivot posts and the other of said pivot posts may escape from the other sets of bearing portions through their slots.

11. In a record cabinet, a plurality of horizontal record-bearing members arranged and adapted to be moved in and out of said cabinet to and from record-displaying positions outside of said cabinet, supporting means movable to and from operative positions to 15 releasably hold said record-bearing members in record-displaying positions, and means connected to said supports and to said cabinet and controlled by said movement of said record-bearing members to and from record- 20 displaying positions for moving said supporting means to and from operative supporting positions below said members.

12. In a record cabinet, a plurality of horizontal, record-bearing trays arranged and adapted to be moved horizontally in and out of said cabinet to and from record-displaying positions outside of said cabinet, supporting legs on said trays movable to and from depending operative positions below said trays 35 to support said trays when outside of said cabinet, and means actuated by movement of said trays to and from record-displaying positions for moving said legs to and from operative positions.

13. In a record cabinet, a plurality of horizontal, record-bearing trays arranged and adapted to be moved horizontally in and out of said cabinet to and from record-displaying positions outside of said cabinet, tail 45 pieces pivoted to said trays for maintaining said trays releasably connected with said cabinet while in their record-displaying positions, legs movably connected to said trays for supporting said trays at predetermined inclinations while in their record-displaying 50 positions and means for moving said legs to supporting position when said trays are moved out of said cabinet.

14. In a record cabinet, a plurality of horizontal, record-bearing trays arranged and adapted to be moved horizontally in and out of said cabinet to and from record-displaying positions outside of said cabinet, tail pieces pivoted to said trays for maintaining 55 said trays releasably connected with said cabinet while in their record-displaying positions, legs movably connected to said trays for supporting said trays at predetermined inclinations while in their record-displaying 60 positions, and means controlled by move-

ments of the trays to and from record-displaying positions for moving said legs to and from operative positions.

15. In a record cabinet, a plurality of horizontal, record-bearing trays arranged and adapted to be moved horizontally in and out of said cabinet to and from record-displaying positions outside of said cabinet, tail pieces pivoted to said trays for maintaining said trays releasably connected with said cabinet while in their record displaying positions, legs movably connected to said trays for supporting said trays at predetermined inclinations while in their record-displaying positions, and operating means for said legs connected to said tail pieces for moving said legs to and from operative position when said trays are moved to and from record-displaying positions.

16. In a record cabinet, a plurality of horizontal, record-bearing trays arranged and adapted to be moved horizontally into and out of said cabinet to and from record-displaying positions outside of said cabinet, supporting legs movably connected to and adapted for engagement with a fixed part of said cabinet to support said trays when outside of said cabinet, and means actuated by movement of said trays to and from record- 95 displaying positions for moving said legs to and from operative positions, said legs being extensible whereby the length thereof may be varied in accordance with the varying distances of said trays from said fixed part of said cabinet.

17. In a record cabinet, a plurality of horizontal, record-bearing trays arranged and adapted to be moved horizontally in and out of said cabinet to and from record-displaying positions outside of said cabinet, means for releasably maintaining said trays connected to said cabinet when drawn out to record-displaying positions, pivots on said trays, legs rigidly connected to said pivots and adapted to swing relatively to said trays for supporting said trays at predetermined inclinations while in their record-displaying positions, crank portions for said legs, rigidly connected to said pivots, and means connected to said crank portions for rocking said pivots to cause said legs to project angularly from said trays as said trays are moved to said inclined positions.

18. In a record cabinet, a plurality of horizontal, record-bearing trays arranged and adapted to be moved horizontally in and out of said cabinet to and from record-displaying positions outside of said cabinet, means for releasably maintaining said trays connected to said cabinet when drawn out to record-displaying positions, pivots on said trays, legs rigidly connected to said pivots and adapted to swing relatively to said trays for supporting said trays at predetermined inclinations while in their record-displaying 125 positions.

positions, crank portions for said legs rigidly connected to said pivots, links connected to said crank portions, and means for moving said links as said trays are moved to and from said inclined positions to rock said pivots and move said legs to and from operative supporting positions in which they project angularly from said trays.

19. A record cabinet having a plurality of open sides, a plurality of record-supporting members in substantially horizontal positions in said cabinet and having front and rear portions, means pivotally and releasably connecting said record-supporting members at one end to said cabinet, whereby said record-supporting members may be pivotally swung out of any one of the open sides of said cabinet, and holding means on said supporting members adapted to engage and cooperate with means on said cabinet for releasably connecting said supporting members to said cabinet, when said members are swung out of said cabinet at either of said open sides.

20. A record cabinet having a plurality of open sides, a plurality of record-supporting members in substantially horizontal positions in said cabinet and having front and rear portions, means pivotally and releasably connecting said record-supporting members at one end to said cabinet, whereby said record-supporting members may be pivotally swung out of any one of the open sides of said cabinet, and a recessed part on each of said supporting members adapted to interfit with parts on said cabinet adjacent said open sides thereof for releasably maintaining said supporting members in their outward positions at either of said open sides of said cabinet.

21. A record cabinet having a plurality of open sides, a plurality of record-supporting members in substantially horizontal positions in said cabinet and having front and rear portions, means pivotally and releasably connecting said record-supporting members at one end to said cabinet, whereby said record-supporting members may be pivotally swung out of any one of the open sides of said cabinet, and a recessed part on each of said supporting members adapted to interfit with holding parts on opposite sides of said cabinet to releasably maintain said supporting members in said outward position at either of said open sides of said cabinet, said holding parts being disposed on said cabinet in alternating relation with said record supporting members.

22. A record cabinet having a plurality of open sides, a plurality of record-supporting members in substantially horizontal positions in said cabinet and having front and rear portions, means pivotally and releasably connecting said record-supporting members at one end to said cabinet, whereby said record-supporting members may be pivotally swung out

of any one of the open sides of said cabinet, means on said supporting members and on said cabinet for releasably retaining said supporting members in said cabinet, said retaining means being adapted to yield to permit 70 said members to be moved out of said cabinet, and holding means on said members adapted to engage parts on said cabinet for maintaining said members in their outward positions at either of said open sides of said cabinet. 75

23. A record cabinet having a plurality of open sides, a plurality of record-supporting members in substantially horizontal positions in said cabinet and having front and rear portions, means pivotally and releasably connecting said record-supporting members at one end to said cabinet, whereby said record-supporting members may be pivotally swung out of any one of the open sides of said cabinet, means for positively locking said supporting members in said cabinet, and means for releasably maintaining said members in said cabinet when said locking means have been released.

24. A record cabinet having a plurality of open sides, a plurality of record-supporting members in substantially horizontal positions in said cabinet and having front and rear portions, means pivotally and releasably connecting said record-supporting members at 90 one end to said cabinet, whereby said record-supporting members may be pivotally swung out of any one of the open sides of said cabinet, means for positively locking said supporting members in said cabinet, means other than said locking means for releasably maintaining said members in said cabinet when said locking means have been released, said means being adapted to yield to permit said members to be moved out of said cabinet, and means for releasably connecting said supporting members to said cabinet, when moved to outward position at either of the open sides of said cabinet.

CERTIFICATE OF CORRECTION.

Patent No. 1,774,239.

Granted August 26, 1930, to

JAMES H. RAND, JR., ET AL.

It is hereby certified that error appears in the printed specification of the above numbered patent requiring correction as follows: Page 3, line 6, for the misspelled word "alinemept" read alinement; page 4, line 46, for the numeral "25" read 35; line 105, for "diengaging" read disengaging; line 121, for "side" read slide, and line 124, for "record" read records; page 5, lines 43 to 44, claim 4, strike out "formed to receive records in overlapping position" and insert having records arranged in overlapping position; and that the said Letters Patent should be read with this correction therein that the same may conform to the record of the case in the Patent Office.

Signed and sealed this 21st day of October, A. D. 1930.

(Seal)

M. J. Moore,
Acting Commissioner of Patents.
